UNITED STATES PATENT OFFICE

JAMES KING, OF CHICAGO, ILLINOIS

PAPER-HANGING DEVICE

Application filed October 30, 1928. Serial No. 316,015.

The object of the invention is to provide a tool or device by means of which paper may be placed on the wall of a room, particularly the ceiling, without the necessity for having 5 to use ladders and scaffolds in the operation; the provide a device by means of which time in the paper hanging operation may be saved, since the several tools employed in the various operations are combined in one application; and to provide a device of this character which is of simple construction and therefore susceptible of cheap manufacture and low marketing cost.

With this object in view the invention consists in a construction and combination of parts of which a preferred embodiment is illustrated in the accompanying drawings, wherein:

Figure 1 is an elevational view of the invention.

Figure 2 is a sectional view on the plane indicated by the line 2—2 of Figure 1.

Figures 3 and 4 are sectional views on the planes indicated by lines 3—3 and 4—4, respectively, of Figure 2.

Figure 5 is a top plan view of the grip bar.

Figure 6 is a detail elevational view of a portion of the handle, illustrating the latching means for the grip bar plunger.

Figure 7 is a sectional view on the plane indicated by the line 7—7 of Figure 6.

Figure 8 is a sectional view on the plane indicated by the line 8—8 of Figure 2.

Figure 9 is an enlarged elevational view 35 of one of the grip bar pins.

The handle 10 by means of which the device is actuated and on which are supported the various elements constituting the complete device is of tubular form, the brush supporting head 11 being carried at the upper end of the handle and comprising, in addition to the ferrule into which the handle telescopes, a pair of spaced parallel brush grippers 14. The grippers 14 are formed preferably from 40 fleet spring steel so as to frictionally engage and therefore securely hold the backs of the brushes 15. This construction provides for the ready removal and replacement of the brushes by the withdrawal of the backs therefrom and the insertion of the same therein.

The grip bar 16 is disposed between the two brushes and in parallel therewith, being normally impelled upwardly by compression springs 17 disposed on opposite sides of the handle and having their ends bearing respectively upon the head 11 and the bar. The bar 16 is carried by a plunger 18 slidably mounted in the handle and provided adjacent the lower extremity of the latter with a pin 19 traversing a bayonet slot in the handle. 55 Since the springs tend normally to keep the grip bar 16 adjacent the plane of the ends of the brush bristles, the bayonet slot and pin serve as a means for latching the grip bar in retracted position adjacent the head 11, where 60 it will be out of position to interfere with the operation of the bristles. 65

The grip bar on the upper face is provided with a series of spaced pins 21, the free ends of the pins being rounded as indicated at 22 to 70 eliminate sharp corners and prevent tearing of the paper being hung. The purpose of the grip bar is to provide a member for gripping so that the sheet may be slid laterally, if necessary, to effect the proper juncture at the 75 seam with the previously hung sheet. The grip bar when so used, is elevated by the springs to approximately the plane of the brush bristles, where the pins may readily engage the sheet and effect sufficient adhesion thereto to permit the sheet being slid slightly without danger of tearing, the rounded corners 22 of the pins preventing the latter from digging into the sheet.

A rest roll 23 is disposed parallel to the 80 brushes, being rotatably supported in the yoke 24 carried by bracket clamp 25 which surrounds the handle, an adjusting bolt 26 and attendant wing-nut 27 serving to bind the clamp on the handle as well as to secure 85 the yoke to the former. Obviously the rest roll may be moved toward or away from the brush head by loosening the yoke and positioning the roll as desired, the roll being raised or lowered on the handle by the shifting of the bracket clamp to the desired position on the latter when the nut 27 is loose. 90

In the use of the invention, the paste is applied to the sheet or strip of paper to be hung and the latter placed over the brushes 100

and across the rest roll 23 with the face downward. It may then be applied to the wall or ceiling by placing the strip or sheet against the wall surface with a sufficient pressure to secure adherence at one point, when the movement of the brushes by means of the handle along the sheet will effect its complete placement, as with the ordinary hand brush.

When the grip bar is not used to effect slight side movement of the sheet in the smoothing out operation, it is retracted and retained in retracted position by latch pin 19. The rest roll 23 serves to support the unattached portion of the sheet in applying the same.

15 The invention having been described what is claimed as new and useful is:

1. A device of the kind indicated comprising a handle, a brush supporting head carried at one extremity of the handle, and a grip bar disposed adjacent the brush supporting head, the grip bar being movable toward and away from the brush supporting head.

2. A device of the kind indicated comprising a handle, a brush supporting head carried at one extremity of the handle, and a grip bar disposed adjacent the brush supporting head, the grip bar being movable toward and away from the brush supporting head, and a pair of brushes carried by the brush supporting head and disposed in parallelism on opposite sides of the grip bar.

3. A device of the kind indicated comprising a handle, a brush supporting head carried at one extremity of the handle, and a grip bar disposed adjacent the brush supporting head, the grip bar being movable toward and away from the brush supporting head, the grip bar on its upper face being provided with a series of uniformly spaced pins.

4. A device of the kind indicated comprising a handle, a brush supporting head carried at one extremity of the handle, and a grip bar disposed adjacent the brush supporting head, the grip bar being movable toward and away from the brush supporting head, the handle being of tubular form and the grip bar having a plunger slidably mounted in the handle and compression springs disposed between it and the head.

5. A device of the kind indicated comprising a handle, a brush supporting head at the upper end of the handle, and a rest roll carried by the handle and adjustable longitudinally thereof and laterally toward and away from the brush carrying head.

6. A device of the kind indicated comprising a handle, a brush supporting head at the upper end of the handle, and a rest roll, a yoke in the extremities of the arms of which the rest roll is journaled, a bracket clamp engaging the handle and the yoke, and a clamp screw carried by said bracket and also engaging the yoke, the latter being swingable toward and away from the handle when

the clamp screw is loosened and the clamping bracket at such time being adjustable longitudinally of the handle.

In testimony whereof he affixes his signature.

JAMES KING.
